UNITED STATES PATENT OFFICE.

GEORGE L. MALONEY, OF WISNER, NEBRASKA.

WINDOW-BRACKET.

1,199,586.

Specification of Letters Patent. Patented Sept. 26, 1916.

Application filed April 11, 1916. Serial No. 90,437.

To all whom it may concern:

Be it known that I, GEORGE L. MALONEY, a citizen of the United States, residing at Wisner, in the county of Cuming and State 5 of Nebraska, have invented new and useful Improvements in Window-Brackets, of which the following is a specification.

This invention relates to improvements in window brackets, and has for its main object the provision of a bracket capable of adjustment to accommodate itself to windows of different dimensions, together with a means for both effecting an adjustment between the parts and holding said parts fixed 15 relatively in their adjusted position.

Another important object of the invention resides in the provision of a construction by means of which a curtain shade, a lace curtain, or drapery may be hung singly or in 20 combination, use being made of a particular form of bracket and pole for this purpose.

The nature and advantages of the invention will be better understood from the following description when read in connection 25 with the accompanying drawing, the invention residing in the construction, combination and arrangement of parts as fall within the scope of what is claimed.

In the drawing forming part of this specification like numerals of reference indicate 30 similar parts in the several views and wherein:

Figure 1 is a fragmentary front elevation of a window showing the bracket secured 35 thereto with the curtain pole removed. Fig. 2 is a top plan view with the curtain pole in use. Fig. 3 is an enlarged detail view of the adjusting means. Fig. 4 is a detail view of one of the curtain pole brackets. 40 Fig. 5 is a sectional view through these parts associated.

Before entering into a detail description of what is herein shown, I desire to have it understood that the same is merely illustrative of one embodiment of the invention 45 to which I do not limit myself, and certain changes may be resorted to within the scope of the claims, without departing from the spirit of the invention.

50 Referring more particularly to the drawing the invention as shown consists of a support for the pole brackets, indicated at A, and a pole indicated at B. The support A includes a pair of relatively adjustable sections 55 10 and 11 respectively which are preferably of channel shaped formation one be-

ing slidably fitted within the other. The outer extremity of each section carries a plurality of projections or spurs 12 adapted to be driven into the opposite sides of the 60 window casing for the purpose of securing the support thereto. The sections as will be readily understood are adapted to be adjusted outwardly to permit the projections 12 to hook over the opposite edges of the 65 window casing, subsequent to which arrangement the sections are adjusted toward each other with a view of embedding the projections in the window casing. These sections may be so adjusted in any suitable 70 manner, but as shown in this particular instance use is made of a link 13 pivoted at one end to the innermost end of the section 10, while pivoted to the opposite end of the link at a point in its length is a lever 14 75 having a lug 15 projecting from the end immediately adjacent its pivot. The section 11 is provided with an extension 16 which is slidably fitted within the section 10, to provide for the adjustment hereinabove 80 mentioned. This extension is provided with a longitudinal series of apertures 17 adapted to interchangeably receive the lug 15 on the lever, so that when the latter is swung upon its pivot in one direction the section 10 is 85 adjusted toward the section 11. Manifestly the lever may be swung upon its pivot in a reverse direction, subsequent to the removal of the lug from said opening which 90 it initially engaged, to permit a new purchase to be had upon the extension 16 by inserting the lug in a different opening therein, sufficient play being provided between the parts to permit of the lever being readily disengaged from the extension when desired. 95 When the section 10 has been moved to the limit of its adjustment, whereupon the projections at the opposite ends of the support A are embedded in the window casing, the lever together with the link 13 are straightened to lie parallel with the support A. In this position the lug 15 is arranged in one of the openings and the hook-like extension 18 carried by the free end of the lever embraces the upper edge of the section 11. 100 The hook-like element functionates to retain the lever in a parallel position with respect to the support, thereby co-operating with the lug 15 to hold the sections of the support fixed relatively in their adjusted position. 105 The section 10 may be adjusted outwardly 110 and away from the section 11 when it is de-

sired to remove the support from the window casing by merely reversing the movement of the lever, or in other words swinging the lever in the direction of the section 5 10 subsequent to the positioning of the lug 15 in one of the openings of the extension 16. There is slidably mounted upon each of the sections 10 and 11 a plurality of pole brackets, the brackets indicated at 20 being 10 arranged innermost on the support, and of the ordinary usual construction to accommodate a window shade pole. The brackets indicated at 21 are substantially of U-shaped formation, the parallel portions 15 of which project outwardly from their respective section, while the cross piece is provided with opposed extensions 23 adapted to be bent about the opposite edges of the support defining the loop by 20 means of which these brackets may also be adjusted upon the support. These brackets are especially designed to accommodate one or two poles of the type illustrated, wherein the poles are of channel formation in cross 25 section, comprising two sections 24 and 25 respectively, the latter being slidably fitted within the former. The outer extremities of each section are curved inwardly and adapted to removably receive the limbs of 30 the brackets 21. By reason of the U-shaped formation of the brackets 21 two of these poles can be used if desired, one for supporting a lace curtain and the other supporting a drapery or the like, it being manifest that each pole employs one limb of 35 each bracket. The parallel limbs of the brackets 21 are preferably provided with depressions 26 adapted to receive suitable depressions 27 formed in the flanges of the 40 pole B adjacent the opposite ends thereof, whereby the poles are effectively held associated with the brackets, but can be easily removed therefrom when desired. It is of course to be understood that only one pole .

may be used, the brackets being of such 45 construction to accommodate two however.

The device in its entirety is not only simple in construction and cheap to manufacture, but the parts are so arranged as to permit of an adjustment between the same 50 to be quickly effected to either attach the bracket to the window or remove the same therefrom when desired.

What is claimed is:—

1. In a device of the class described, a 55 support, a bracket mounted upon the support adjacent each end thereof and capable of sliding movement thereon, each of said brackets including spaced parallel limbs, and a pole of channel-shaped formation in 60 cross section having its extremities curved inwardly to receive one of the limbs of each bracket.

2. In a device of the class described, a support, brackets slidably mounted thereon 65 and each including spaced parallel limbs, a pole of channel formation in cross section having its extremities curved inwardly to receive one limb of each bracket, and said limbs having notches therein to receive depressions in the extremities of said pole to 70 hold the parts fixed relatively.

3. In a device of the class described, a support including adjustably associated sections, a bracket slidably fitted upon each 75 section and including spaced parallel limbs, a pole including telescopic sections of channel formation in cross section, and each section having its outer end curved inwardly to receive a limb of one of said brackets. 80

In testimony whereof, I affix my signature in presence of witnesses.

GEORGE L. MALONEY.
